CRANKCASE DRIP PAN

Joseph C. Delk, Jr., 1825 Raleigh Road,
Asheboro, N.C. 27203

Filed Mar. 20, 1968, Ser. No. 11,076

Term of patent 14 years

U.S. Cl. D14—6
Int. Cl. D12—14

FIG.1

FIG. 1 is a front perspective view of a crankcase drip pan embodying my design;

FIG. 2 is a top plan view of FIG. 1;

FIG. 3 is a front elevational view of FIG. 2;

FIG. 4 is a transverse sectional view along line 4-4 of FIG. 2;

FIG. 5 is an end elevational view of FIG. 3; and

FIG. 6 is a transverse sectional view along line 6-6 of FIG. 2.

I claim:

The ornamental design for a crankcase drip pan, as shown.
